ELECTRICAL SWITCH

Harry J. Mabs, Chicago, Ill., assignor to James E. Johnson, Chicago, Ill.

Application June 7, 1937, Serial No. 146,842

1 Claim. (Cl. 200—11)

This invention relates to an electrical switch. More particularly the invention is concerned with the type of switch wherein at least one pair of contacts are mounted for relative movement transversely of the current path between the contacts for making and interrupting an electrical circuit, and wherein at least one of the contacts is arranged to reciprocate along lines substantially normal to the direction of relative movement.

It will be understood that in such a switch the reciprocable contact is normally yieldably urged toward a position at which engagement between the contacts will be effected during the relative movement thereof and the engagement will be at a pressure sufficient to assure suitable electrical contact but insufficient to introduce undue friction or enough friction seriously to interfere with the relative movement.

The invention includes among its objects the provision of a novel and an improved switch of the type mentioned, and a novel contact for such switch which is longitudinally reciprocable but which is held against rotation about its longitudinal axis, which is economical to make, which may be readily assembled in such a switch, which is adapted to make a substantially linear, as distinguished from a point or surface, contact, which is so constructed as to minimize wear on a lead or conductor connected thereto and the connection therewith, and the novel combinations and arrangements of elements hereinafter disclosed and claimed as illustrated in the accompanying drawing showing an embodiment of the invention wherein like reference characters refer to similar parts throughout the several views.

In the drawing:

Figs. 1 and 2 are more or less diagrammatical views, respectively showing fragments of plan and transverse cross sections of a switch embodying the features of the invention;

Fig. 3 is a fragmentary cross section through one of the novel contacts with the contact member shown partially in cross section and partially in side elevation;

Fig. 4 is a view similar to that shown in Fig. 3, but looking in the direction of the arrows 4—4 of Fig. 3; and

Fig. 5 is a cross section taken substantially along the lines 5—5 of Fig. 4.

As diagrammatically illustrated in Figs. 1 and 2, an electrical switch of the type referred to hereinbefore comprises a pair of plate-like or other suitable contact carrying members 11 and 12 which are arranged in spaced relation for rela-

tive movement, for example, about a common axis of a post or shaft 13. The direction of relative movement is substantially parallel to the members 11 and 12, or, stated in slightly different terms, the direction of relative movement is transversely of the electrical current path between the switch elements. One of the contact carrying members, for example the contact carrying member 12, is provided with one or more contact members 14 on its surface, facing the 10 other contact carrying member, and each contact member 14 is electrically associated with a binding post or terminal 15 at the opposite surface of the contact carrying member 12 to facilitate connecting each contact member 14 15 in circuit by, for example, a conducting lead 16.

It will be understood by those skilled in the art to which this invention pertains, that a contact member for each of the contact members 14 is correspondingly arranged on the contact carrying member 11 for engaging and disengaging with the contact members 14, respectively, during the relative movement of the contact carrying members 11 and 12.

The contact members for engaging the members 14 have heretofore been provided in the form of elongated tubular or cylindrical members having enlarged, substantially flat heads at the contact ends. The shanks of those contact members were slidably and yieldably arranged 20 in apertures through an insulating member or strip 17 suitably secured, as at 18, to the contact carrying member 11. When so arranged, the contact heads faced the contact carrying member 12 and normally were yieldably urged 30 to positions adjacent the surface thereof carrying the contact members 14.

During relative movement of the contact members 11 and 12 transversely of the electrical current path between such contact members, the 40 contact heads and the corresponding contacts 14 would slidably engage one another, the contact heads yielding to permit such sliding engagement. In such operation, the elongated contact member would rock or oscillate about its longitudinal axis, thus twisting and thereby straining the lead conductor and its connection with the contact member, and sometimes breaking the lead or its connection with the contact member.

In order to overcome that difficulty and to provide a more efficient contact, I employ for the reciprocable contact, as shown in Figs. 3 to 5, an elongated strip 19 having at one end a flat head portion 21 of contact material of greater 50 55

width than the strip shank, and at its opposite end a connection terminal portion 22. The terminal portion 22 may be provided with an aperture 23 therein to facilitate connecting the contact in circuit by a suitable lead conductor

5 24. The head portion 21 of the contact is preferably hardened by hammering, and is formed with a line contact portion 25 and with beveled ends 26.

10 15 20 For slidably mounting such a contact to prevent rotation or rocking thereof, I provide a bushing of tubular form having a limiting external flange 27 intermediate its ends, a passage 28 leading from one end of the bushing into communication with a larger passage 29 at the other end of the bushing and providing an internal shoulder 31 intermediate the ends of and inside the bushing, and a pair of slots or grooves 32 extending longitudinally of the bushing at diametrical sides thereof in the walls of the passage 28.

25 30 35 In assembling the novel contact, a coil spring 33 is arranged about the shank of the elongated contact with one end abutting the contact head portion 21. The other end of the shank is inserted in the outer end of the passage 28 and arranged in the guide slots 32. The elongated contact is then moved into the bushing, bringing the end of the spring 33 opposite the head portion 21 into abutting relation with the flange 27. By compressing the spring, the terminal end of the elongated contact may be projected through the passage 29 and outside of the bushing whereby to facilitate bending the contact, as at 34, to cause the terminal portion 22 to cooperate with the internal shoulder 31 in holding the spring urged elongated contact and bushing in assembled relationship.

40 45 50 One or more such assembled contacts, depending upon the number of contact members 14 employed in the switch, are secured to the insulating member 17 by forcing that end of each bushing including the large passage 29 into an aperture in the insulating member, the external flange 27 serving to limit the movement of the bushing during that assembly operation. In thus assembling the contact and mounting means, I arrange the contact head with its line contact portion 25 extending in the direction of relative movement transversely of the electrical current path so that the beveled ends 26 may serve as cam surfaces engageable with the corresponding con-

tact 14 to compress the spring 33 whereby to permit sliding contact of linear characteristics between corresponding contact members during the relative movement of the contact carrying members.

5 10 15 20 Thus I secure the electrical advantages of line contact and in addition, with a minimum of friction, a firm wiping electrical contact. The slots or grooves 32 serve not only to guide each elongated contact in its reciprocable movement, but also to prevent it from rotating or rocking about its longitudinal axis. In that manner twisting strains on the leads 24 and their connections with the contact members are minimized, if not entirely eliminated, with the advantageous result 15 of durable connections of the novel contacts in circuit.

25 30 While I have described a specific embodiment of the invention, it will be understood that the invention is not limited to the precise details set forth hereinbefore, but that many changes and modifications may be made without departing from the spirit or scope of the following claim.

Having thus described my invention, what I claim as new and desire to secure by Letters 25 Patent of the United States is:

30 35 40 45 50 An electric switch comprising a contact, a circuit closure means cooperating therewith comprising a bushing movable in a direction substantially transverse the direction of flow of current through the switch, said bushing having internal longitudinal slots and an internal annular shoulder, an external flange on said bushing intermediate the ends thereof constituting a limiting stop for the bushing upon inserting the portion thereof at one side of the flange in an apertured support, a conductor member of strap form slidably disposed in said slots and provided with a shouldered contact head at one end, a spring disposed between said head and said external flange for urging said conductor member and contact head in a direction axially of the bushing for effecting engagement of said head with said contact, and a conductor terminal at the other end of said conductor member comprising an integral portion of the latter offset from the plane of the remaining portion thereof and arranged to abut said internal shoulder for limiting axial movement of the conductor member by said spring.

HARRY J. MABS.
